UNITED STATES PATENT OFFICE.

JOHN W. COX, OF ERIE, PENNSYLVANIA.

APPARATUS FOR EMPTYING RECEPTACLES.

1,283,090.

Specification of Letters Patent. Patented Oct. 29, 1918.

Application filed February 3, 1917. Serial No. 146,509.

To all whom it may concern:

Be it known that I, JOHN W. Cox, a subject of the King of Great Britain, having declared my intention of becoming a citizen 5 of the United States, residing at Erie, in the county of Erie and State of Pennsylvania, have invented new and useful Improvements in an Apparatus for Emptying Receptacles, of which the following is a specification.

10 This invention relates to an apparatus for emptying receptacles and consists in certain improvements in the construction thereof as will be hereinafter fully described and pointed out in the claims.

15 The object of the invention is to provide a simple and efficient means for emptying receptacles. It is particularly advantageous in emptying receptacles in which castings are annealed in forming malleable castings.

20 Here the mass formed by the annealing material and the castings can only be loosened by subjecting the receptacle to considerable shock. The separation of the castings from the residue of the annealing material is also 25 desirable.

The invention is illustrated in the accompanying drawings as follows:—

Figure 1 shows a side elevation of the apparatus.

30 Fig. 2 an end view from the right of Fig. 1.

1 marks a tilting frame which is pivotally mounted by means of a hinge 2 upon a base 3. Shafts 4 are journaled in bearings 5 on 35 the tilting frame. The shafts 4 have the supporting pulleys 6 in which tracks 7 on the drum 8 travel. This arrangement of shafts as 4 with the pulleys and track is a common form of mounting for rotating 40 drums.

A frame 9 is supported on the posts 10 extending upwardly from the frame 1 and a motor, preferably an electric motor 11 is mounted on the frame 9. The motor drives 45 a pulley 12 and a pulley 13 is driven from the pulley 12 by a chain or belt 14. The pulley 13 is mounted on a shaft 15 and the shaft 15 is carried by bearings 16 on the frame 9. A pulley 17 is mounted on the shaft 15 and 50 drives a pulley 18 by means of a belt or chain 19. The pulley 18 is mounted on a shaft 20 and the shaft 20 is mounted in bearings 21 arranged in brackets 21^a extending from the posts 10. A pulley 22 is mounted 55 on the shaft 20 and drives by means of a chain or belt 23 a pulley 24 on one of the

shafts 4. In this manner the drum is rotated. The tilting of the frame 1 does not break the driving connection.

It is desirable to have a charging device 60 for the receptacles and I have provided a charging platform 25. It is pivoted at 26 on a bracket 27 extending upwardly from the base 3. The platform has two faces, the face 28 being in a horizontal position with the 65 platform in its lower position and the face 29 with the platform in elevated position. The face 28 with the platform in the lower position is flush with the floor so that the receptacles may be readily moved upon it and 70 the face 29 is in alinement with the opening in the drum so that the receptacles can be readily moved from the platform into the drum. Any convenient means of elevating the platform may be used but I prefer a fluid 75 actuated hoisting device for this purpose. A cable 31 is secured to the platform and extends over the pulleys 32 and 33. The pulleys 33 are carried by a rod 34 secured to a piston 35. The piston 35 operates in a cylinder 36. The cylinder and the pulley 32 are mounted on a frame 37 carried by the posts 38. A pipe 39 supplies the cylinder 36 with fluid. This pipe is carried to a control platform or station 41 and is there provided with a controlling valve 40. The operation of the hoist is apparent. When the fluid is turned into the cylinder, it moves the piston, carrying with it the pulleys 33 thus drawing up the cable 31 and with it the 80 platform 25.

In order to move the loaded receptacles from the platform to the drum a sweep 42 is provided. This is in the form of a swinging arm with a rod 45. The rod 45 is secured to 95 a piston 46. The piston 46 operates in a cylinder 47. The cylinder 47 is carried by a frame 48 supported on the posts 38. A pipe 49 carries fluid to the cylinder. This pipe is carried to the control station or platform 41 and is there provided with a controlling valve 50. The operation of this feature can be readily understood. When the platform has been elevated it brings the receptacle to the position shown in dotted lines in Fig. 1 100 with the sweep 42 to the rear of the receptacle. When fluid is admitted to the cylinder, it moves the sweep forward, carrying with it the loaded receptacles and moving them into the drum.

105 In order to discharge the drum, it is desirable to tilt the drum and this is done by tilt-

ing the supporting frame. The frame 1, as before stated, is pivoted at 2. The opposite end of the frame 1 is carried by links 52. The links 52 extend upwardly and are connected by a cross head 53. The cross head is pivotally connected by means of a link 53^a with a rod 54. The rod 54 is secured to a piston 55. The piston 55 operates in a cylinder 55^a. The cylinder is supported by a link 56 which extends from a cross piece 57 forming a part of the frame 37. A pipe 58 extends from the cylinder past the control station or platform 41 and is provided with a controlling valve 59. When the fluid is exhausted the frame 1 drops by gravity, thus tilting the drum. When the drum is in operation, the platform is held in its upper position by turning fluid under the piston 55 so as to hold the frame 1 in its upper or horizontal position.

The drum has openings 60 through which the refuse material which is contained in the receptacles may pass. In order that very severe shock may be given to the receptacle 25 the interior of the drum is supplied with ribs 61 ordinarily formed of railroad iron and extending longitudinally of the drum.

As the drum is rotated the receptacles 30 are subjected to very severe shock so that the material such as annealed castings are 35 entirely loosened from the receptacle and to some extent the receptacles are emptied in the drum itself. The rolling of the receptacle in the rotating drum accomplishes this loosening to some extent but this is accentuated by the use of the projections or ribs which not only assures the rolling of the receptacle in the drum but also localizes the blow on the sides of the receptacle as it rolls. The receptacles are cleared of refuse 40 material and this passes out of the openings in the drum. When the castings are entirely loosened the drum is tilted, thus emptying the castings and the receptacles from the 45 drum. In this manner the emptying of the receptacles is very easily accomplished.

What I claim as new is:—

1. In an apparatus for emptying receptacles, the combination of a drum open from 50 end to end to permit the passage of a receptacle through it and having a receiving end to receive a receptacle and having an unobstructed discharge opening to permit the discharge of a receptacle by gravity when the drum is tilted; a mounting for the drum; means for rotating the drum; and means for 55 tilting the drum to give to the drum an inclination to discharge material from the discharge end of the drum by gravity.

60 2. In an apparatus for emptying receptacles, the combination of a drum open from end to end to permit the passage of a receptacle through it and having a receiving end to receive a receptacle and having an unob- 65 structed discharge opening to permit the dis-

charge of a receptacle by gravity when the drum is tilted, said drum having peripheral openings to permit the escape of material from the drum; a mounting for the drum; means for rotating the drum; and means for 70 tilting the drum to give to the drum an inclination to discharge material from the discharge end of the drum by gravity.

3. In an apparatus for emptying receptacles, the combination of a drum open from 75 end to end to permit the passage of a receptacle through it and having a receiving end to receive a receptacle and having an unobstructed discharge opening to permit the discharge of a receptacle by gravity 80 when the drum is tilted, said drum having longitudinal ribs on its inner periphery; a mounting for the drum; means for rotating the drum; and means for tilting the drum to give to the drum an inclination to discharge 85 material from the discharge end of the drum by gravity.

4. In an apparatus for emptying receptacles, the combination of a drum open from 90 end to end to permit the passage of a receptacle through it and having a receiving end to receive a receptacle and having an unobstructed discharge opening to permit the discharge of a receptacle by gravity when the drum is tilted; a mounting for the drum; 95 means for rotating the drum; means for tilting the drum to give to the drum an inclination to discharge material from the discharge end of the drum by gravity; a charging platform; and means for elevating said 100 platform to the level of the opening at the receiving end of the drum whereby a receptacle may be moved from the platform into the drum while supported by the platform and drum.

5. In an apparatus for emptying receptacles, the combination of a drum open from 105 end to end to permit the passage of a receptacle through it and having a receiving end to receive a receptacle and having an unobstructed discharge opening to permit the discharge of a receptacle by gravity when the drum is tilted; a mounting for the drum; means for rotating the drum; means for 110 tilting the drum to give to the drum an inclination to discharge material from the discharge end of the drum by gravity; a charging platform; means for elevating said platform to the level of the opening at the receiving end of the drum whereby a receptacle may be moved from the platform into the drum while supported by the platform and drum; and a sweep for moving the receptacle from the platform to the drum.

6. In an apparatus for emptying receptacles, the combination of a drum open from 115 end to end to permit the passage of a receptacle through it and having a receiving end to receive a receptacle and having an unobstructed discharge opening to permit 120

the discharge of a receptacle by gravity when the drum is tilted; a mounting for the drum; means for rotating the drum; means for tilting the drum to give to the drum an 5 inclination to discharge material from the discharge end of the drum by gravity; a charging platform; means for elevating said platform to the level of the opening at the receiving end of the drum whereby a receptacle 10 may be moved from the platform into the drum while supported by the plat-

form and drum; a sweep for moving the receptacle from the platform to the drum; and controlling devices for controlling the tilting of the drum, the elevation of the platform and operation of the sweep, said controlling devices being arranged at a common point. 15

In testimony whereof I have hereunto set my hand.

JOHN W. COX.
